TURBINE

Charles W. Galuska, San Jose, Calif. (Vinnel Corp. of California, Unit 2, APO 358, San Francisco, Calif.), assignor of fifty percent to Lois Edwards, San Jose, Calif.

Filed June 2, 1958, Ser. No. 739,256

5 Claims. (Cl. 60—60)

This invention relates to turbines and more particularly to a combination turbine adapted to be actuated by water under pressure flowing adjacent thereto.

An object of the invention is to provide a combined turbine adapted to connect with a source of flowing water, the turbine having a pair of coupled units which combine to provide for a power take-off. Water under pressure passing through a conduit is the ultimate motive force used to operate the units of the turbine. A venturi is applied in the conduit with a pipe attached to the suction or low pressure part of the venturi, and the turbine that is constructed in accordance with the invention connected with this pipe. The first unit is adapted to be rotated by the air which rushes through the pipe to enter the venturi, while the second unit reduces the atmospheric pressure adjacent to and in the pipe to further facilitate operation of the first unit. This second unit also applies a suction to the first unit which operates with the suction produced at the venturi, even further aiding in rotating the first unit of the combined turbine.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a diagrammatic perspective view showing a typical installation of the invention.

Figure 2 is an enlarged sectional view taken on the line 2—2 of Figure 1.

Figure 3 is a sectional view taken on the line 3—3 of Figure 2.

Figure 4 is a sectional view taken on the line 4—4 of Figure 2.

Figure 5 is a sectional view taken on the line 5—5 of Figure 2.

Figure 6 is a sectional view taken on the line 6—6 of Figure 4.

Figure 7 is a sectional view taken on the line 7—7 of Figure 1.

In the accompanying drawings there is a typical installation 10 which has the invention embodied therein. This installation includes a dam 12 having a conduit 14 that leads to power house, filtration plant, or the like 16. Conduit 18 is the discharge conduit from the building housing the filtration plants, power house, etc. A venturi 20 is in conduit 18, and the venturi has a low pressure part with an opening 22 in registry therewith. A housing 24 encases a part of the conduit and opening 22 with which pipe 26 is registered.

As shown in Figure 2 the pipe 26 has an opening 28 in registry with an opening in casing 30. The end of the pipe 26 has an opening 32 in registry with sleeve 34 that is attached to one end of the casing 30. The air that is drawn into the venturi 20 through pipe 26 must pass through opening 28 or through opening 32, but opening 32 has unit 36 connected with it which main-

2

tains a vacuum within the sleeve 34 and housing 62 of unit 36 and accordingly prevents air from flowing inwardly through opening 32 to pipe 26. Accordingly, all of the air that enters the venturi passes through opening 28.

Casing 30 has a turbine wheel 38 mounted for rotation on a turbine wheel shaft 40. This is rotatably disposed in bearings 42 and 44 that are carried by the end walls of casing 30. The end of turbine shaft 40 can have splines 46 thereon or any other type of coupling for connection to any kind of device needing power to operate it. A typical device would be a dynamo or generator.

The air to the inlet for the unit 48 having the turbine wheel 38 therein, is passed through an air filter 50 consisting of a case 51 with filter material 52 in it and a screen 53 covering the filter material. An air tube 54 is connected with an opening in the air filter casing and connected with an air inlet opening 56 in casing 30. 20 Mounting flanges and bolts can be used for attaching all of the pipes, conduits and the like in place. In addition, although only a few seals are illustrated, it is understood that seals can be used wherever found necessary or desirable.

Shaft 40 extends through sleeve 34 and is mounted for rotation with a bearing 60 carried by housing 62. The housing 62 is a part of a rotor of unit 36 and includes a cylindrical side wall 64 mounted for rotation on the open end of sleeve 34. Seal 66 is disposed between the cylindrical wall 64 and the open outer end of sleeve 34. Shaft 40 is keyed or otherwise fixed to the bearing 60 so that the rotor of unit 36 is actuated simultaneously with the rotation of the turbine wheel in the first unit 48.

A plurality of hollow radial arms 68 are attached to the walls 64 and they have venturi tubes 70 at their outer ends and in registry with the passageway in each hollow arm 68. The direction of rotation of the rotor of unit 36 is shown in Figure 3. When so moving the air rushes through the venturi tubes 70 causing a suction in the passageways of each arm. This suction draws a draft through the venturi tubes 70, they acting as a discharge for the air. Therefore the cavity enclosed by housing 62 is under a vacuum as is the space enclosed by sleeve 34. This reduces atmospheric pressure at the opening 28 and helps to drive the turbine wheel 38.

Throttle valve 72 which can be a gate valve or any other type of valve, is attached to air tube 54 in such a way that the control element of the valve can be adjusted to open and close the passage in the air tube 54 and in advance of air manifold 74 that is bolted or otherwise attached to the casing 30 and in registry with opening 56 therein.

In use, the combined turbine is connected so that source of flowing water as shown in Figure 1 induces a reduced pressure in pipe 26. Valve 72 is adjusted in accordance with the desired speed of operation, this controlling the air inlet to the first unit 48 containing the turbine wheel 38. At the same time, the second unit 36 has its rotor set in motion because the rotor is coupled to shaft 40 of the first unit 48. This draws a further vacuum at the inlet 28 of the first unit turbine casing 30 further aiding in the operation of the unit 48.

The foregoing is considered as illustrative only of the principles of the invention. Further, since numerous modifications and equivalents may be resorted to, it is not desired to limit the invention to the exact construction and operation shown and described.

What is claimed as new is as follows:

1. A combination turbine having a first unit and a second unit, said first unit including a casing having a pair of openings defining an air inlet and outlet, said air inlet being open to the atmosphere, a turbine wheel shaft

mounted for rotation in said casing, a turbine wheel fixed to said shaft, said second unit including a rotor, means on said rotor for drawing a vacuum, an air pipe communicating said outlet opening with said means for drawing a vacuum, said rotor operatively connected to said shaft and driven thereby, a venturi through which water passes having an opening at the low pressure part thereof, said air pipe further connected to the opening in said venturi whereby air is drawn through said casing from said inlet to said outlet.

2. A combination turbine having a first unit and a second unit, said first unit including a casing having a pair of openings defining an air inlet and outlet, said air inlet being open to the atmosphere, a turbine wheel shaft mounted for rotation in said casing, a turbine wheel fixed to said shaft, said second unit including a rotor, means on said rotor for drawing a vacuum, an air pipe communicating said outlet opening with said means for drawing a vacuum, said rotor operatively connected to said shaft and driven thereby, a venturi through which water passes having an opening at the low pressure part thereof, said air pipe further connected to the opening in said venturi whereby air is drawn through said casing from said inlet to said outlet, valve means supported adjacent said air inlet operatively interposed between said inlet and said atmosphere for regulating the actuation of said turbine wheel.

3. A combination turbine having a first unit and a second unit, said first unit including a casing having a pair of openings defining an air inlet and outlet, said air inlet being open to the atmosphere, a turbine wheel shaft mounted for rotation in said casing, a turbine wheel fixed to said shaft, said second unit including a rotor, means on said rotor for drawing a vacuum, an air pipe communicating said outlet opening with said means for drawing a vacuum, said rotor operatively connected to said shaft and driven thereby, a venturi through which water passes having an opening at the low pressure part thereof, said air pipe further connected to the opening in said venturi whereby air is drawn through said casing from said inlet to said outlet, said means on said rotor for drawing a vacuum including a plurality of hollow radial arms, a hollow hub from which said radial arms protrude, said arm hollows communicating with said hub hollow, and venturi tubes at the outer ends of said radial arms.

4. A combination turbine having a first unit and a second unit, said first unit including a casing having a pair of openings defining an air inlet and outlet, said

air inlet being open to the atmosphere, a turbine wheel shaft mounted for rotation in said casing, a turbine wheel fixed to said shaft, said second unit including a rotor, means on said rotor for drawing a vacuum, an air pipe communicating said outlet opening with said means for drawing a vacuum, said rotor operatively connected to said shaft and driven thereby, a venturi through which water passes having an opening at the low pressure part thereof, said air pipe further connected to the opening in said venturi whereby air is drawn through said casing from said inlet to said outlet, valve means supported adjacent said air inlet operatively interposed between said inlet and said atmosphere for regulating the actuation of said turbine wheel, said means on said rotor for drawing a vacuum including a plurality of hollow radial arms, a hollow hub from which said radial arms protrude, said arm hollows communicating with said hub hollow, and venturi tubes at the outer ends of said radial arms.

5. A combination turbine having a first unit and a second unit, said first unit including a casing having a pair of openings defining an air inlet and outlet, said air inlet being open to the atmosphere, a turbine wheel shaft mounted for rotation in said casing, a turbine wheel fixed to said shaft, said second unit including a rotor, means on said rotor for drawing a vacuum, an air pipe communicating said outlet opening with said means for drawing a vacuum, said rotor operatively connected to said shaft and driven thereby, a venturi through which water passes having an opening at the low pressure part thereof, said air pipe further connected to the opening in said venturi whereby air is drawn through said casing from said inlet to said outlet, valve means supported adjacent said air inlet operatively interposed between said inlet and said atmosphere for regulating the actuation of said turbine wheel, said means on said rotor for drawing a vacuum including a plurality of hollow radial arms, a hollow hub from which said radial arms protrude, said arm hollows communicating with said hub hollow, and venturi tubes at the outer ends of said radial arms, a sleeve, said hollow hub mounted for rotation on said sleeve, a seal between said hollow hub and said sleeve, said sleeve registered with said air pipe.
